UNITED STATES PATENT OFFICE!

LAWRENCE STROM, OF LOS ANGELES, CALIFORNIA.

ART OF SEPARATING LIQUIDS AND APPARATUS THEREFOR.

968,206.

Specification of Letters Patent. Patented Aug. 23, 1910.

Application filed November 23, 1909. Serial No. 529,605.

To all whom it may concern:

Be it known that I, LAWRENCE STROM, citizen of the United States, residing at Los Angeles, in the county of Los Angeles and State of California, have invented certain new and useful Improvements in the Art of Separating Liquids and Apparatus Therefor, of which the following is a specification.

My invention aims to provide a novel process for physically splitting up and separating, into their two constituents, mixtures of oil with water or other similar liquids by the aid of a mechanical separating device, the use of which constitutes the basis of the process. "Oil" is used here in the generic sense including oils of mineral, animal and vegetable origin.

In the exploitation of oil wells the presence of water mixed in greater or less proportion with the petroleum product plays a most important part. As not infrequently in some oil regions the water in the mixture coming from the ground exceeds the petroleum in amount, means must be adopted to eliminate the useless ingredient, and in view of the enormous volumes to be handled and the comparatively low price of the product such means must be inexpensive and capable of treating the mixtures very expeditiously. Again mixtures of water with oil are formed as the result of lubricating and running machinery. Such mixtures occur most frequently in the crank cases, bearing cases and save-alls of practically universal use in modern high-class engineering, especially where positive pressure feed lubrication prevails. Leakage from glands and the water commonly used for cooling hot parts run into these receptacles, there forming a mixture with the oil that has drained from moving parts or been delivered by the lubricating pumps. This, while the most common, is but one of many ways in which such oil-water mixtures are formed in modern industry. It having been found that the oil of such mixtures may perfectly well be used over again almost indefinitely, after being separated from the water, and cleaned, that is, freed from any entrained dirt, especially metallic particles abraded from the working surfaces, numerous processes and devices have been put into use to achieve the separation. Most are based on the difference in specific gravities between the two ingredients; again on the difference in specific heats, again on the effect of centrifugal

force. All of the methods so far used have the defect of requiring considerable time to produce the separation of large volumes of mixtures; and, in many cases, to secure more rapid separation of the oil, large installations have been resorted to at great expense.

It is to secure water-free oil at a minimum expense of time and prime cost of installation that the present process and apparatus have been devised. To obtain separation of the liquid I feed it upon a rapidly revolving hood, shed or turtle-back, the movement producing motion of the liquid in a circular direction by entraining it and in a radial direction owing to the centrifugal component; whereby it is hurled from the shed in a small jet forming a sweep curving radially outward and backward from the point of leaving the disk, owing to the forces acting tangentially and radially upon it. This sweep I find to be of great importance in attaining the full efficiency of my apparatus or method. It presents the mixture to the selector-blades in a body having much greater depth than thickness, increasing the volume of liquid exposed to the blades and insures that these are constantly immersed in a bath of the mixture while the machine is in operation. Upon leaving the shed the mixture now in the form described is dashed against a series of fixed selector-blades. I consider that the separative effect is due to the two actions. In the movements of rotation and ejection from the shed the cohesion of the particles is to a large extent broken as one observes in water running from a faucet, in rapids and water-falls. In this condition the tendency is for molecules of the same substances to form drops, in other words to unite with one another, like to like. Upon encountering the fixed blades which offer sharp edges to the on-coming, already partially physically disassociated masses of mixture these are entirely broken up, the water forming spray and drops and being thrown off, while the oil, owing to its superior viscosity adheres to the blades and by gravity runs down their sides to a suitable receptacle.

In view of the foregoing, my invention consists in the art or process and in the apparatus for carrying out said process, as hereinafter described and claimed.

The apparatus in which the mixture is subjected to the above process is illustrated in the accompanying drawings in which—

Figure 1, is an elevation partly in section of the separator, as mounted on a factory floor, the supporting platform and parts above it being in section; Fig. 2, a top plan view of the separator proper, the parts above the bearing platform being removed; Figs. 3 and 4 are detail views of one of the selector-blades, Fig. 5 is an elevation of two separators coupled in tandem and Fig. 6 is an elevation partly in section of the separator as mounted on a floor.

A platform 2 resting on pillars or suitable angle iron supports 3, rising from the shop-floor 4 to which they are secured as usual, serves to support the machine and its driving shaft 6. The receiving and collecting vessel 7, a sheet metal receptacle of any suitable shape but preferably as here shown with a short upper cylindrical part 7^a joined to a part 7^b having the form of a hollow truncated cone is provided at the rim with a broad flange 8 extending inwardly from the rim as well as outwardly which preferably slopes downward from in, out. This flanged rim serves to support the apparatus by means of the hangers 9 having their lower ends bent at right angles 10 engaging under and riveted or bolted to flange 8 while the upper similarly bent ends are secured by any suitable means to platform 2 or as here shown. An angle-brace 11 is provided for the platform support to upright 3 with its upper arm long enough to take the bolts for securing the hanger 9, which bolts then pass through the angle-brace and the platform. The drive-shaft 6, carries integral with it a collar 12 provided with a ball-race 13 working on a fixed bearing portion 14 bolted to the platform. This fixed portion 40 also carries a vertical bearing 15 to secure the lateral alinement of the shaft, the upper end of which is steadied laterally by vertical bearing 16 supported from the platform as shown. At its lower end the drive-shaft 45 has secured to it by known means the hood or shed 17, which may be no more than a flat disk of sheet metal, but is preferably a hollow truncated cone or a segment of a sphere in both cases of very small altitude, about from 1/25 to 1/30 of its diameter, and is adapted to rotate in a horizontal plane. This is to cause the liquid to be shed more rapidly as it is normally sluggish in moving owing to its viscosity. The periphery 50 of the hood extends to about one inch inside of and slightly above the inner edge of the rim-flange 8 of the oil receiver. The annular clearance space 18 is used to accommodate the selector-blades 19 which are riveted 60 or bolted to the under side of inner part of flange 8 by means of their flat root portion 19^a, being secured so as to point toward the center of the hood in their general direction. As seen in Figs. 3 and 4 each blade 65 curves downward and inward beyond the

root portion, then turns almost straight upward with reference to distance toward or from the center, but at angle preserved uniform from the point of upwardly turning of from 25 to 30 degrees backward, with reference to the direction of rotation of the shedding hood. The blades come up from the annular clearance space 18, in which they are represented by the dotted lines at 20, the straight portion passing to about one 75 half inch above the hood's edge and within 1/32 of an inch therefrom, being inclined inward or toward the center at an angle of 5° from the vertical in that direction. Forward and backward being here understood 80 to refer to the direction of gyration of the hood. The rear edge of the flat portion of the blades is chamfered off at any suitable angle to present a sharp, knife-like edge 21 to the curving jets of mixture, while the upper part 22; of the front edge is eased off at an angle to meet the rear edge in a sharp point. Each of these different parts and shapes has its especial effect on the mixture segregation, being the results of many different trials and changes of form. A circular dam is worked upon the inner edge of the rim flange 8 in order to prevent any water that has been eliminated from the oil-mixture from running back into the oil 95 receiver 7 from the outwardly sloping rim flange through the annular clearance space 18.

A pulley 24 is here shown keyed to the drive-shaft to transmit to it the necessary 100 turning power by belt from any suitable source of energy. Gearing or direct drive by a motor placed on the platform may also be used to turn the shaft, which for best working should make from 112 to 175 revolutions per minute.

In operating the mixture is delivered by a pump or by gravity through a pipe 25, preferably terminating in a circularly bent portion 26, having a suitable number of 110 holes or slits at the bottom and discharging over the opening bounded by a broad ring 27, which may be made of a short length of pipe, and is secured by several short legs 28 to the top of the shedding hood 17. Under 115 the action of the compound forces previously described and of gravity the mixture of oil and water fed thus upon the hood is thrown in the sweeping curve characteristic of this invention from the hood's edge 120 against the knife-edges of the selector-blades. These break up the jets completely, selecting by its viscosity the oil from the mixture in the manner already set forth, which oil adhering to the sides of the blades, 125 runs down along these into receiver 7, whence it is drawn off through drain cock 29 into a suitable receptacle or conduit 30, the sloping sides of portion 7^b assisting the running down of the torpid liquid. Where 130

the quantity handled is great as in large central light and power stations, handling crude oil from wells and the like, a pump 5 may be connected to the bottom of the receiver to deliver the oil to the cleaning or filtering apparatus or to barrels or tanks. The water thus eliminated from the mixture drops for the larger part on the rim-flange. This may advantageously be provided with 10 a trough 31 running underneath it, into which it can discharge the water through apertures 32 made at a suitable pitch. A drain pipe 33, connected with the drainage system of the plant carries off the water 15 from the trough. To prevent the water from slopping over the edge of the rim-flange 8, the latter may advantageously be turned up at its outer edge forming a circular dam 34.

20 While the pitch of the selector-blades is to some extent influenced by the nature of the oil handled and the proportion of oil to water in the mixture I have found for general practice to meet normal conditions $\frac{1}{2}$ to 25 1 inch to be satisfactory. The heavy cylinder oils used on valve stems, piston rods and frequently on step bearings and turbine main bearings work with a less close pitch than do the light machine and spindle oils 30 because they adhere more readily to the selector-blades and usually come with a smaller proportionate admixture of water. Similarly the dark, heavy, viscous mineral oils drawn from deep wells are handled by 35 separators in which there are fewer selector-blades spaced farther apart than they would be with the light hydrocarbon oils rich in naphthas, benzin and similar volatile compounds.

40 Instead of using a single circle of blades I may stagger them in two circular series the blades of one circle being in echelon with those of the other; or I may advantageously 45 arrange two blades side by side by having one project beyond the other from a common point of riveting.

In general, a single separator, run at the proper speed to suit the class of mixture efficiently handles a surprising quantity of 50 oil-water liquid, but where it is important to operate quickly yet to insure that no water whatever appears in the resulting oil the tandem effect illustrated in Fig. 5 gives the best results. The construction and operation 55 are plain from the drawing and the foregoing description, the working being precisely the same as for one, with the exception that the mixture fed by the first unit on to the second is already relatively so free from water that the selector blades of the second 60 may be set at a much wider pitch than those of the first. A triple effect machine may also be made by extension of the same construction.

65 In many cases the platform here shown

may be dispensed with by hanging the separator from the ceiling, running the shaft and feeding the mixture from the floor above; or the shaft may be run through a stuffing-box in the bottom of the receiver and supported 70 in a step bearing secured in the shop floor. In the latter case the friction in the stuffing-box forms a serious drawback and the shaft is apt to cut very quickly in the stuffing-box by sand and dirt carried in by the oil. Nevertheless 75 for the equipment of well-drilling crews of the itinerant type, who work from one well to another until the oil supply is exhausted the hanging construction of Fig. 1 is out of the question. For such temporary plants I have designed the form shown 80 in Fig. 6. The construction is clear from the drawing, being merely an adaptation of the former to special conditions. The collar 12 in this case is formed on the lower end of the shaft, the fixed bearing portion 14 is bolted with countersunk bolts to the bed plate 34, or whatever foundation be used. On the outside of the ball-race 13, and shoulder 12 the bearing 15 is bolted to secure the 85 shaft laterally, while its upper end is similarly secured by bearing 16 set into cross-beam 35 resting on posts or pillars 36, which in the case of well outfits will probably be driven into the ground. The drive pulley 90 24 is preferably placed low down to bring the pull of the belt near the lower laterally holding bearing, which is necessarily much more firm than the upper one. In order to avoid the use of a stuffing-box in the oil receiver 7 which would soon cause the shaft 95 to cut and would produce great friction, the shape of the tank is in this case changed by the introduction of the tube 38 which surrounds the shaft as far up as the rim of the 100 receiver. The latter is supported and steadied by a suitable number of stays 39 run to the bed-plate, floor or ground. The above described apparatus is comparatively light 105 and small, as I have found that separators of from 2 feet up to 4 feet in diameter suffice for all ordinary cases.

While the preceding specification uses oil-water mixtures as an illustration it is evident that the same process and apparatus 115 are applicable to any mixtures of ingredients differing in their viscosities and adhesion.

What I claim as new and desire to have protected by Letters Patent is the following:

1. A process for physically separating into 120 their constituents mixtures of liquid substances differing in viscosity, consisting in precipitating said mixture against obstructions by centrifugal force which causes the more viscous of said constituents to separate 125 from said mixture and adhere to said obstructions and then collecting said more viscous constituents.

2. The process for separating fluid mixtures, consisting in passing said mixture in 130

- 2
- a finely divided condition, over a conducting surface; and forcing said mixture into contact with separated obstructions to which the viscous liquid will adhere and which will 5 lead said viscous substance away and leave the non-viscous substance to be separately dealt with.
3. A process for physically separating a mixture of liquids differing in adhesive-ness into its constituents consisting in imparting to said mixture circular motion and, at the same time, motion in direction of the 10 instantaneous radius of the circular path passing through any particle of said mixture, projecting said mixture into space under the combined effect of the forces producing said motions, physically scattering said mixture into spray and drops, leading away the more viscous substances of said 15 mixture, over a conducting surface, to a receiver, and leaving the less viscous substance to be separately dealt with:
4. A process for physically separating oil and water in admixture into its constituents, 20 consisting in feeding said mixture onto a rapidly revolving surface, ejecting said mixture from said surface by centrifugal force, dividing the ejected mixture into spray and drops by projecting it against an obstacle, 25 and leading the oil of the mixture along the surface of said obstacle to a receiver leaving the water of said mixture to be separately dealt with.
5. A process for physically separating a mixture of oil and water into its constituents, 30 consisting in feeding said mixture onto a rapidly revolving surface near the center thereof, driving said mixture from said surface by centrifugal force against the knife-edges of sharp selector-blades, and leading 35 the oil of said mixture along the sides of said selector-blades by gravity coating with adhesion, to a receiver, leaving the water to be separately dealt with.
- 45 6. A separator for mixtures of a viscous with a non-viscous liquid consisting of rotating means for imparting to said mixture circular motion and radial motion with reference to said rotating means, means for 40 projecting said mixture from said rotating 50

means, fixed means for breaking up said mixture after projection, into spray and drops, and for conducting said viscous liquid adhering to said means to a separate receptacle.

7. An apparatus for separating a mixture of oil and water into its constituents consisting of a mixture shedding hood having means for being rotated, a series of selector-blades fixed in a circle, each having a knife edge presented against the direction of revolution of said hood, and flat sides of which the inner is located very close to the periphery of said hood, and a sharp point projecting above the edge of said hood, an oil receptacle underneath said hood having a broad rim-flange extending both inward and outward of the rim and to within a short distance from and below the edge of said hood, said selector-blades being secured to the under side of said rim-flange, crossing the open annular space between it and said hood and coming up through said space, means for preventing the washing back of water from said rim-flange into said space, 75 means for drawing off oil from said receptacle; means for feeding liquid onto said hood at its center and distributing said feed.

8. In an apparatus for separating a mixture of oil and water into its constituents, a selector-blade having a straight, flat root portion with means for securing it to a fixed flat surface in said apparatus, a U shaped portion curving downward from the inner end of said flat portion, the other arm of said U extending upward beyond said flat portion not less than the total height of said U, and inclined at an angle of not more than 65 nor less than 60 degrees to said flat portion, a knife edge formed on one edge of 90 said prolonged arm, a long chamfer on the opposite edge forming a point at the end of said knife-edge.

In testimony whereof I affix my signature in presence of two witnesses.

LAWRENCE STROM.
